Patented Aug. 6, 1918.

UNITED STATES PATENT OFFICE.

HARRY B. SMITH, OF BROOKLYN, NEW YORK, AND JAMES D. REIFSNYDER, OF PHILADELPHIA, PENNSYLVANIA, ASSIGNEES TO STOKES & SMITH COMPANY, OF SUMMERDALE, PENNSYLVANIA, A CORPORATION OF PENNSYLVANIA.

FORM-BLOCK FOR BOX-COVERING MACHINES.

1,274,801.

Specification of Letters Patent.

Patented Aug. 6, 1918.

Application filed January 13, 1915. Serial No. 2,043.

To all whom it may concern:

Be it known that we, HARRY B. SMITH and JAMES D. REIFSNYDER, citizens of the United States, residing at Brooklyn, county 5 of Kings, State of New York, and Philadelphia, county of Philadelphia, and State of Pennsylvania, respectively, have invented new and useful Improvements in Form-Blocks for Box-Covering Machines, of 10 which the following is a specification.

The present invention relates in a general way to box covering machines of the type wherein a one-piece covering blank is applied and affixed to the bottom, side and 15 end walls of a paper box shell, and more particularly the invention has to do with an improved construction of form block for use in connection with machines of the general type illustrated and described in Letters 20 Patent No. 691,329, dated January 14, 1902, and No. 744,122, dated November 17, 1903.

Box covering or wrapping machines of this general type usually include a two-part form block, and a coöperating platen arranged to support and carry the box shell and its cover or wrapper past the covering instrumentalities which usually comprise rollers or brushes for applying the side and end wings of the blank or wrapper to the 30 sides and ends of the box, and past what are known as "edge tuck-in fingers" for turning the marginal edges of the covering blank over the upper edges of the box shell, preparatory to tucking the said marginal

35 edges down onto and affixing them to the inner faces of the walls of the box. This operation of tucking down and affixing the marginal edges is usually accomplished by the upper part of the two-part form block after 40 the cover paper or wrapper has been applied to the sides and ends of the box. In performing this operation, the two form block parts are held separated while the edge tuck-in fingers push the marginal edges of the wrapper 45 or cover over the upper edges of the box, and the upper part of the two-part form block is then allowed to move down into the box, carrying with it the turned in marginal edges of the cover paper. After this operation 50 has been performed, presser blocks im-

part a pressure upon the outer walls of the box adjacent to the marginal edges so as to firmly affix the inturned portions of the cover or wrapper to the inner walls of the box.

Machines of this type are usually made adjustable in order to provide for the manufacture thereon of boxes of different sizes, that is to say, different in width, length and depth, and said machines as heretofore constructed have usually been provided with solid form blocks. This being true, it is obvious that for each size of box manufactured on the machine, form blocks having a corresponding size must be provided.

According to the present invention, we provide a two-part form block in which the upper part or upper block is relatively thin or shallow, and is made adjustable both laterally and longitudinally to accommodate boxes of different sizes.

Inasmuch as the prime function of the upper form block part is to turn down the marginal edges of the wrapper or cover while the major portion of the box is being supported upon the other form block part, and between it and the platen, it is essential that this adjustable form block part shall have a substantially continuous tucking-in edge around the lower marginal portion thereof and substantially continuous sides with no projecting portions because of the pressure imparted to the box walls by the pressure blocks.

A principal object of the invention is to produce a two-part form block such as referred to above, in which the upper block which turns in the projecting edges of the box cover may be readily adapted to operate upon boxes of different dimensions, but which will always present at the edge of the block which contacts with the cover, a continuous edge extending in such a way that the bending force exerted upon the cover is exerted continuously and simultaneously throughout the entire length of the box.

The invention resides mainly therefore in a box covering machine embodying a two-part form block and coöperating platen

combined with edge tuck-in fingers, the upper part of the form block being laterally and longitudinally adjustable and having a substantially continuous turning in marginal edge on the under side thereof and separate means for supporting and operating the two form block parts in order that they may be separated at the proper time to permit the operation of the edge turn-in fingers.

A further object of the invention is to provide a very simple construction for a two-part form block enabling it to be readily adapted for operating upon boxes of any depth or horizontal dimensions within certain limits.

A further object of the invention is to provide yielding means on the block enabling the clamping bolt to secure all the parts simultaneously; that is, all the parts which it clamps.

Further objects of the invention will appear more fully hereinafter.

The invention consists in the general combination of parts and simplicity of details hereinafter described, all of which contribute to produce efficient box covering devices.

A preferred embodiment of our invention will be particularly described in the following specification, while the broad scope of our invention will be pointed out in the appended claims.

In the drawings:—

Fig. 1 is a side elevation of a form block and indicating a box in cross-section in process of having the marginal edges of the cover folded over the upper edges of the side walls of the box, preparatory to having the upper part of the form block descend to cause the same to adhere to the inner face of the box wall. In this view certain parts are represented as broken away.

Fig. 2 is a perspective showing the upper part of the form block disconnected and shown partly broken away and in section to further illustrate details of its construction.

Fig. 3 is a perspective showing one of the corner sections of the upper block detached from the other parts.

Fig. 4 is a perspective showing a part of the device in detail.

Fig. 5 is a plan showing the upper form block in its smallest or most collapsed condition corresponding to the smallest box which can be covered with this form block.

Fig. 6 is a vertical section taken about on the line 6—6 of Fig. 2.

Referring more particularly to the parts, and particularly to Fig. 1, in which we show a two-part form block; this form block comprises an upper block 10 and a lower block 11. These blocks during part of the operation of the machine are together, that is, the

upper block 10 lies directly against the upper face of the block 11. Near the completion of the process of applying the cover 12 to the box, and particularly to the side walls 13 thereof, the lower block 11 lies at the bottom of the box 14 and holds the same upon a platen 15. The position of the lower block 11 is controlled by a stem or rod 16 which is attached to its upper face by a plate 17, and this rod 16 passes downwardly through the upper block 10. The position of the upper block 10 may be controlled in any suitable manner, as for instance, by two small stems or rods 18 which attach to the upper plate 19 carrying the upper block. At the stage of the operation shown in Fig. 1, the upper block 10 has risen slightly above the upper edge of the side walls of the box, and at this time, tuck-in fingers 20 are moved inwardly by automatic mechanism so that their inner ends engage the upwardly projecting marginal edges 21 of the box cover and turn the same inwardly into a nearly horizontal position; the cover will have been previously smeared with an adhesive. The upper block 10 then descends and remains in the box; and then its lower edge as it descends engages the projecting edges 21 so as to fold the same downwardly about the upper edges of the box. Presser blocks 20 then move inwardly and press the outer side of the box, to force the tucked in edge against the inner faces of the walls of the box and cause these edges to adhere thereto in a well understood manner. The upper and lower blocks are then withdrawn from the box and the operation of covering the box is then complete.

If it is desired to apply a cover to a box of different depth, it is only necessary to substitute for the block 11 a block having the required depth. These blocks 11 are preferably of fixed dimensions and are therefore preferably formed of wood or similar inexpensive material, and there is a block provided corresponding to each depth of box which is to be covered.

The upper block 10 however, is adapted to coöperate with blocks of different horizontal dimensions or sizes and for this purpose, the upper block is preferably made expandable from the smallest size to the largest sizes. In expanding the upper block to adapt it to the larger sizes a difficulty occurs from the fact that in expanding the block there is a tendency to form a non-continuous folding edge at the lower portion of the upper block so that the marginal edge of the cover to be turned in would not be engaged at all points. Where this occurs, it usually results that the turned in edge does not fold neatly against the inner face of the wall of the box and there is a tendency to pucker or crease the cover where the edge

of the block becomes non-continuous. Furthermore, if pressure is applied to the exterior of the box, while the upper block is in place, in order to insure a close adhesion of the turned in edge, there is a tendency to emboss the wall of the box or its covering at the points where the edge of the upper block is non-continuous.

In order to overcome this defect and to produce a form block with a continuous edge coöoperating with the lower form block 11, we prefer to construct the upper form block 10 of a plurality of corner sections A, B, C, and D, which are four in number and of very similar construction. These corner sections are of angular form comprising extensions or legs which project parallel with the longitudinal axis of the block and other extensions or legs which project parallel with the transverse axis of the block. The two corner sections A and B are preferably formed respectively with slots a' and b' . These slots lie transversely of the block and aline with each other and at the points where these slots are formed, the legs a' and b' of the corner sections A and B overlap each other and are provided with abutting guide faces 22. At these abutting faces 22, channels or grooves a^2 and b^2 are formed in the legs a' and b' to receive a tongue 23 which fits neatly in the alining grooves. (See Fig. 6.) This tongue 23 is held in place by a through-bolt 24 the head of which seats on the aforesaid plate 19; the shank of the bolt passes through a slot 25 which extends longitudinally of this plate. The shank of this bolt extends downwardly and the lower end receives a nut 26 which has a boss with flat side faces 27 to hold the nut when tightening the bolt. Evidently the sections A and B may be pulled apart so as to widen the block 10, and when being separated in this way, they will be guided upon each other; by clamping up the bolt 24, evidently they may be clamped in any desired relation. These corner sections present straight or flat side faces 28 which aline with each other, that is, they are flush with each other in a vertical plane, and aline with the side faces 50 of the lower block with which the upper block is employed. These faces terminate at vertical edges 29 which come together or abut when the form block is in its most contracted or collapsed condition.

We provide means for forming a continuous edge between the vertices of the block, and by way of example we shall describe the manner of doing this between the vertex a^3 of the corner section A and the vertex b^3 of the corner B. For this purpose, we prefer to provide alining means, preferably in the form of a filler or plate 30 and we provide a number of these fillers corresponding to the different widths desired for the form

block, and these fillers fit into the gap or space which is formed between the edges 29 when the block is expanded. These fillers or plates 30 have plane faces which lie flush with the faces 28 of the corner sections and in the same vertical plane therewith. Furthermore, the lower edges of these fillers aline with the lower edges 31 of the side faces 28.

These fillers are preferably arranged to be clamped by the same means that clamps the corner sections together. For this purpose we prefer to make a part of the block yielding or compressible. The fillers may be held in place by means of rabbet grooves or shoulders 32 on the overlapping extensions a' and b' of the corner sections, and we provide the inner face of the filler 30 with a tongue 33 which projects into these grooves in such a way that when the corner sections are clamped together by means of the bolt 24, the plate will be held securely in position. It is understood of course, that when the filler is in position in this way, its ends abut against the edges 29. We prefer to make these fillers the yielding part, and therefore form these filler pieces of a slightly compressible material such as wood.

The connection between the corner sections B and C is preferably substantially similar to that just described for connecting the corner sections A and B, except that there is only one slot employed to permit the longitudinal extension of the block, which is the slot c illustrated most clearly in Fig. 2. However, the corner section C has an extension or leg c' which projects over and slides along a corresponding extension or leg b^4 on the corner section B. The adjacent faces of the legs c' and b^4 have elongated grooves c^2 and b^5 in which there is held a nicely fitted tongue 34; this tongue is held in place by a clamping bolt 35 which passes down through the slot c , the lower end of said bolt being threaded in a boss such as the boss 36 shown in Fig. 6. Evidently the tongue 34 will guide the leg c' longitudinally on the leg b^4 and maintain perfect alinement of the side face c^3 with the side face b^6 of the corner section B. In the gap 37 formed between the vertical edges 38 we provide a filler or plate similar to the filler 30 and held in place in the same manner, that is, by means of rabbet grooves 39 formed in the legs of the corner sections.

On the opposite side of the block 10 there is a clamping bolt 40 similar to the bolt 35 and performing the same function. The other parts at this point, as illustrated, are substantial duplicates of those with which the bolt 35 coöperates to permit the extension and clamping of the corner sections in their extended relation. These parts include a slot a^4 through which the bolt passes.

At the end of the block opposite the bolt 24, a clamping bolt 41 is provided passing through a slot 42 similar to the slot 25 and having the same functions. Coöoperating 5 with this bolt 41, the corner sections C and D have parts, as illustrated, corresponding to and duplicating those described in connection with the corner sections A and B, and including slots c^4 and d^4 .

10 From this arrangement it will be evident that the block may be extended on all sides and when extended, the side faces of the block are maintained in alinement in a vertical plane, and when the block is clamped 15 in its expanded or extended relation, the corner sections will have been moved to a more distant relation with respect to each other, in which they can be held fixed. When the 20 length of the block is reduced as greatly as possible, of course, the bolts 24 and 41 occupy the inner ends of their corresponding slots 25 and 42.

The lower edges 31 of the side faces of the corner sections A, B, C and D are preferably slightly beveled and the members or 25 filler means 30 are preferably formed with a similar beveled lower edge 43 so that the block when enlarged, presents not only continuous side faces extending between the vertices of the corner sections, but it also presents continuous lower edges lying in the same horizontal plane and extending continuously around the periphery of the block.

In order to make the corner pieces as light 30 as possible, we prefer to construct them substantially in the way illustrated in Fig. 3, with openings 44 in the corners. The stem 16 which supports the lower block 11 passes freely through an opening 45 in the plate 40 19. In order to attach the two stems 18 for raising and lowering the upper block, we prefer to provide threaded openings 46 in the plate 19 and these openings are preferably arranged in diagonal relation with respect to the block.

One of the advantages arising from forming the fillers 30 with a part of slightly yielding or compressible material, is that when the clamping bolts 24, 35, 40 and 41 50 are tightened up, to clamp the corner sections together, they will compress the tongues 33 on the fillers and hold the fillers in place. If these fillers were formed of less compressible material such as metal, a very accurate fit would be necessary in order to enable them to be clamped securely by the same bolts that clamp the corner sections together, because if the tongues 33 were too wide they would tend to prevent the bearing 55 faces 22 of the corner sections seating together properly; and if the tongues 33 were too narrow the fillers would not be securely held in place.

In securing the yielding effect for clamp-

ing the parts of the block together, we do 65 not limit ourselves to the particular construction set forth.

It is understood that the embodiment of the invention described herein is only one of the many embodiments or forms the invention may take, and we do not wish to be limited in the practice of our invention nor in our claims to the particular embodiment set forth.

What we claim is:—

1. An expansible form block for a box covering machine comprising four corner sections with flat side faces having lower, inwardly beveled, marginal edges, means for guiding said corner sections so as to maintain the outer faces thereof in alinement with each other respectively whereby said corner sections may be moved away from each other to assume a more distant relation with gaps between the corner sections, and independent removable filler plates received in said gaps, said filler plates having flat faces of the same depth as the outer side faces of the corner sections and also having lower beveled marginal edges alining with the lower beveled marginal edges of the corner sections. 90

2. An expansible form block for a box covering machine comprising four corner sections with outer faces adapted to aline respectively and adapted to fit into the corners of a box which is being covered, said corner sections being movable away from each other to assume a more distant relation and to form an enlarged block, alining removable filler plates having faces alining in a vertical plane flush with the outer faces of the corner sections and coöoperating therewith to form substantially continuous side faces of the block and extending between the vertices of said corner sections, and clamping means for clamping said corner sections together and simultaneously clamping the filler plates in position, said filler plates having tongues projecting into grooves formed in the corner sections. 105

3. An expansible form block for a box covering machine comprising corner sections with flat outer side faces to fit into the corners of a box which is being covered, the lower marginal edges of said corner sections being inwardly beveled, means for guiding said corner sections so as to maintain the outer faces thereof in alinement with each other respectively and enabling said corner sections to be moved away from each other to assume a more distant relation with gaps between the corner sections, removable fillers received in said gaps having flat, vertical faces of the same depth as the flat, outer side faces of the corner sections and alining with such outer faces of the corner sections and having lower, inwardly beveled marginal edges alining with the inwardly beveled 115 120 125

marginal edges of the corner sections, said
filler plates also having parts of compressible
material received between said clamping
shoulders, and means for clamping said
corner sections together and simultaneously
clamping said fillers therebetween.

In testimony whereof we have hereunto

set our hands in presence of two subscribing
witnesses.
